UNITED STATES PATENT OFFICE

WARREN K. LEWIS, OF NEWTON, MASSACHUSETTS, AND NATHANIEL E. LOOMIS, OF ELIZABETH, NEW JERSEY, ASSIGNEES TO STANDARD OIL DEVELOPMENT COMPANY, A CORPORATION OF DELAWARE

ART OF OBTAINING PRODUCTS FROM HYDROCARBONS BY HEAT TREATMENT

Application filed March 30, 1923. Serial No. 628,947.

This invention relates to the art of obtaining products from hydrocarbons by heat treatment, and will be fully understood from the following description, reference being 5 had also to the accompanying drawings, in which—

Fig. 1 is a vertical section through one form of apparatus contemplated in the invention; and

10 Fig. 2 is a similar view of a modification.

In the drawing, the reference character 1 designates a furnace chamber suitably arranged to be heated by oil-burners or coal or other desired fuel. A suitable heat-radiating 15 material 2, for example, refractory checker-work or the like, is heated by the furnace gases; and in position to receive radiant heat from such radiating surfaces is a pipe coil or conduit 3 which receives 20 feed oil, introduced into the system, for instance by inlet pipe 4. Connecting on from the coil 3 is another coil 5 placed in another compartment and out of position to receive radiant heat from the radiating surfaces at

25 2. This coil is heated predominantly by the hot products of combustion which pass on from the furnace through the compartment 6 and finally escape up the stack 7. The cross-sectional area of the passage 6 may be 30 narrowed in order to insure a flow-rate as desired for the hot products of combustion.

As already indicated the oil entering the system passes through coil 3 and is initially heated predominantly by the radiant heat. 35 Proceeding on through the coil 5 the temperature ultimately desired is attained from the hot combustion gases.

If preferred, the coils may be so connected up that the oil on leaving coil 3 is introduced 40 into the last row of coil 5 so as to flow through such coil counter-currently to the direction of the hot products of combustion.

For furnace-efficiency a high fire-box temperature is advantageous, but as this may 45 result also in too much heat in the upper part of the checker-work or radiating element, it is desirable to provide temperature-control means. To this end, a flue 8, Fig. 2, may tap off relatively cool gases from the stack, a blower 9 of any suitable type being

arranged to forward such gases to the furnace. A damper 11 may be provided to shut off the stack and a damper 12 of adequate size may be located in the flue to supply cool air from the outside. Additionally a slide 55 or damper 10 may be located at the front, and by either or all of these the temperature in the radiant mass may be controlled as desired.

When the apparatus described is used for 60 cracking oils, the temperature in the series-connected coils may be from about 725 to 1000° F., and the pressure may be about 250 to 1000 lbs. per square inch. It will be understood that this invention is not limited 65 to any particular method of cracking and the conditions may be varied as desired.

While we have described our invention with reference to certain specific details, it will be understood that this is for purpose 70 of illustration, to make the invention clear, and is not limitative; and changes may be made which come within the spirit and scope of the invention.

We claim:

1. Process for heating oil comprising 75 burning fuel, passing the combustion products so formed through and out of a zone wherein they encounter a large number of surfaces adapted for heat absorption and 80 radiation, heating a stream of oil by radiation from said zone and convection, passing said stream of oil into a space shielded from radiation, further heating said stream in 85 said space by indirect heat exchange with combustion products passing from said zone, and regulating the temperature of said zone by return of cool combustion products thereto.

2. Process for heating oil, comprising 90 burning fuel, passing the products of combustion so formed through and out of a zone wherein they encounter a large number of surfaces adapted for heat absorption and 95 radiation, substantially uniformly distributing such radiation over a stream of the oil to be heated, maintaining said stream at all times remote from contact with the flame of the burning fuel but in indirect heat exchange with combustion gases, passing said 100

stream of oil into a space shielded from radiation, and further heating said stream in said space by heat transfer from said combustion gases after they have emerged from said heat radiating surfaces and said indirect heat exchange.

3. Process according to claim 2 in which the temperature of the combustion zone is regulated by return of cool combustion products thereto for admixture with the hot gases after the greater part of the combustion has taken place therein.

4. Oil heating apparatus, comprising a combustion furnace, a series connected pipe coil, a heat radiating checkerwork between the source of furnace gases and the coil, a second coil connected to receive a stream of oil from said coil and out of heat radiation range of said checkerwork, and means for returning combustion gas, after contact with said second coil, to the checkerwork, whereby the temperature of the checkerwork may be controlled.

5. Oil heating apparatus, comprising a combustion furnace, a series connected pipe coil, a checkerwork arranged to shield the coil from freshly generated combustion gases and to absorb and radiate heat to the coil, and a second coil connected to receive a stream of oil from said coil and out of heat radiation range of said checkerwork.

6. Oil heating apparatus, comprising a combustion furnace, a series connected pipe coil, a checkerwork arranged to shield the coil from freshly generated combustion gases and to absorb and radiate heat to the coil, means for causing the furnace gases to flow through the checker-work so as to uniformly heat the same, and a second coil connected to receive the stream of oil from the first mentioned coil and out of heat radiation range of said checker-work.
